CLAIM

The ornamental design for a tablet computer with removable scanning device, as shown and described.

DESCRIPTION

FIG. 1 is a front perspective view of a tablet computer with removable scanning device showing our new design.

FIG. 2 is a front elevation view thereof.

FIG. 3 is a back elevation view thereof.

FIG. 4 is a top plan view thereof.

FIG. 5 is a bottom plan view thereof.

FIG. 6 is a right elevation view thereof.

FIG. 7 is a left elevation view thereof; and,

FIG. 8 is another front perspective view thereof with the scanning device removed from the tablet computer.

The broken line barcode illustrates environment and forms no part of the claimed design.

1 Claim, 6 Drawing Sheets
